S. W. JAMESON

SHAFT KILN CONSTRUCTION

Filed April 25, 1924

UNITED STATES PATENT OFFICE.

STEWART W. JAMESON, OF DULUTH, MINNESOTA.

SHAFT-KILN CONSTRUCTION.

Application filed April 25, 1924. Serial No. 708,865.

This invention relates to kilns.

This invention has utility in connection with shaft kilns for calcining rock. The structure of this disclosure is one peculiarly adapted for handling limestone in quantity with a minimizing of matters of upkeep due to the temperature take-up features. Furthermore, the temperature is dissipated in its development about the kiln not only in the base structure but in the lining as to the shell structure.

Referring to the drawings:

Fig. 1 is a plan view, with parts broken away, of a cylindrical type of shaft kiln;

Fig. 2 is a fragmentary side elevation of the kiln of Fig. 1;

Fig. 3 is a detail view of the discharge valve or gate for the kiln;

Fig. 4 is a detail view of a joint between sections of a shell showing in dotted lines the take-up or flange distortion of such joint;

Fig. 5 is a fragmentary plan view of a battery or wall of rectangular kilns; and

Fig. 6 is a partial side elevation of the kilns of Fig. 5.

Support or base 1 is shown as having thereon furnaces 2 in communication with flue 3 of cylindrical shaft kiln having refractory lining 4, backing masonry lining 5, and insulation lining 6. These linings 4, 5, 6, are housed by a metallic shell herein shown as sections 7 having outwardly extending terminal flanges 8, and therebetween upper and lower outwardly extending flanges 9. In practice, it may be economical to have the flanges 8 integral with the sheet or section extent, while when this sheet or section is out of a plane the connecting upper and lower flanges are advantageously formed and connected to the section 7. These flanges 8, 9, serve as stiffening or reinforcing means for the shell section. These shell sections provide joints 10 vertically extending, intersecting joints 11 horizontally extending, thereby providing four-corner joints between sections. These sections are independently removable, thereby permitting repair of any local defect in any of the kiln linings.

The shell sections, due to their flange assembly, while sufficiently substantial to withstand holding strains from the kiln linings, still involve features of yielding circumferentially. This yielding is an enlargement take up due to the outward

spacing of assembling bolts or rivets 12 as connecting the flanges 8. As the linings expand, due to warming up of the kiln, the flanges 8 may distort or slant toward each other as the linings enlarge. This means that throwing strains on the section assembly means may not be disastrous. It further means that the shell section holding is effective for maintenance of continuous shell assembly. This avoids any crushing or disintegration strains upon a lining. It means that the voids in the insulation are not eliminated. This is a factor in maintaining the effectiveness of the insulation. The vertical or longitudinal expansion, of course, may be outward from the shell, but in the event of adherence, any strains between the flanges 9 as united by the bolts or rivets 12 may be automatically cared for by flange distortion as in the cooperation between the flanges 8.

When a kiln is shown as built up from a main support or floor 1, there is provided therebelow a discharge floor 13. From the kiln flue 3, there is a downwardly extending chute or cone 14 having a terminal opening 15. Into this cone, the calcined rock, say from lime carbonate to quick lime, travels and is in a heated state approximating incandescence as the calcining temperature may run in the flue 3 to 1700° F. or greater. This chute 14 is a region in which it is desired to have the temperature lowered without detracting from the efficiency of the kiln operation. The great load carried by the main support or floor 1 may be accomplished by girders or boxed beams 16, herein shown as provided with lattice filling 17 in the region of the upper portion of the chute 14. This means that there is no trapping of the highly heated air as rising about the unlined chute 14, but that such air may freely pass away from the upper region of this cone or chute 14, thereby increasing the rate of cooling for the cone 14.

As the quick lime in the cone 14 has its temperature reduced such may be withdrawn at intervals as desired. To this end, the opening 15 has on opposite sides thereof, guides 18, 19, in which members 20 are reciprocable toward each other into valve closing position at the opening 15. Each of these members 20 has link 21 extending therefrom. Second-class lever 22 is connected to one of the links 21 and fulcrumed

100

105

110

on the guide 18. The other link 21 is connected to first-class lever 23, fulcrumed on the guide 19. (Fig. 3). Link 24 between the levers 22, 23, completes this assembly 5 of the valve or gate control mechanism in a common plane so that rocking of the lever 23 toward the lever 22 will result in opening the valve for lime discharge from the opening 15, while reverse swing of this lever 23 10 will simultaneously shift the members 20 as slideable along the guides 18, 19, into closed position for the opening 15.

Flues 25 are shown as rectangular and with series of linings 26, 27, 28, assembled 15 to form a wall hollow at the flues 25. This (Figs. 5, 6) type of shaft kiln has economy in reducing the volume of radiation by reducing the exposed area of the kiln. Furthermore there is maximum flue area for 20 the general kiln space occupied. This wall is shown as housed by sections 29 having upper and lower flanges 30, end flanges 31, as to the side section. This section 29 is further stiffened by I-beams 32 held by truss-rods 33 25 extending between flanges 31 into assembly with the section 29. They have four-corner joints with the adjacent sections, but in the intermediate region between the flues 25 tie-plates 34 may break joints, and thereby one 30 plate serves as a tie-means for sections as meeting on the outside. Filler plate portions 35 may be disposed between the flanges 31 as to the opening between successive tie-plates 34. These tie-plates 34 are preferably 35 of less gauge than the outer shell sections 29, but in any event, the assembly of such sections 34 to be anchored to said shell at the flanges 31 is such that bolts or rivets 12 may have greater shear resistance than the pull 40 of the tie-plates 34 so that the holes in the tie-plates 34 are enlarged by expansion strains, and the bolts 12 hold up for maintaining assembly between the flanges 31. At the end of the wall plates or shell sections 36 45 are shown having flanges 30, 31, with the stiffening I-beams 32 and tie-rods 33. These sections 36, 29, are independently removable for purposes of flue up-keep. Angle corners 37 connect the flanges 31 of the plates 29, 36.

What is claimed and it is desired to secure 50 by United States Letters Patent is:

1. A shaft kiln structure embodying refractory lining means, a shell for said lining, said shell comprising sections having flanges 55 bounding on a common section side and extending at an angle to the section extent, said flanges of adjacent sections approximating parallel relation, and means offset from the directional extent of one section for connecting its flanges with the flanges 60 of the abutting sections, whereby kiln lining expansion strains may distort said flanges with the connecting means still effective.

2. A shaft kiln structure embodying refractory lining means, and a shell for said 65 lining comprising peripherally flanged sections independently removable and providing four-corner meeting joints between said sections, said flanges being exteriorly accessible and exposing flange connecting 70 means accessible exteriorly of the kiln.

3. A shaft kiln embodying a lining, a shell exterior of the lining comprising a stiffened laterally removable section for exposing the lining, said section having an endless outwardly projecting flange directed away from the lining, and exteriorly exposed flange-engaging means for assembling the section in the shell to envelop said lining. 75

4. A shaft kiln provided with a metal 80 shell, a support therefor including a beam having transversely thereof openings therethrough, and a chute for said kiln depending from the shell and extending below said beam, whereby the openings in the beam 85 permit free air circulation about the chute adjacent the base transversely of the beam.

5. Shaft kilns embodying adjacent refractory linings as a continuous wall, a common shell for a plurality of said kilns embodying sections having joints terminating between the shaft portions of said kilns, and tie means extending between the linings of adjacent kilns and anchored with the shell at 90 said joints. 95

In witness whereof I affix my signature.

STEWART W. JAMESON.
